(57) **CLAIM**

The design related to gun, compressed air gun or gun model, as shown and described.

DESCRIPTION

FIG. 1 is a front perspective view of the gun, showing our new design;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof;

FIG. 8 is a rear perspective view thereof;

FIG. 9 is a front perspective view showing a variation of our new design;

FIG. 10 is a left side view of FIG. 9;

FIG. 11 is a right side view of FIG. 9;

FIG. 12 is a front view of FIG. 9;

FIG. 13 is a rear view of FIG. 9;

FIG. 14 is a top view of FIG. 9;

FIG. 15 is a bottom view of FIG. 9; and,

FIG. 16 is a rear perspective view of FIG. 9.

The broken lines shown are included for the purpose of illustrating the unclaimed portions of the article and form no part of the claimed design.
